PORTFOLIO

Sam W. Brunner, Flushing, N. Y.

Application November 4, 1954, Serial No. 32,959

Term of patent 14 years

(Cl. D87—3)

Fig. 1

Fig. 2

Fig. 3

Fig. 1 is a front view of the portfolio, showing my new design,

Fig. 2 is a top view thereof partially broken away for purpose of illustration;

Fig. 3 is a rear view thereof;

Fig. 4 is a corner portion of the right side of the portfolio shown in Figs. 1, 2 and 3, on an enlarged scale, and

Fig. 5 is an enlarged view of Fig. 4 taken on lines 5—5 showing the cross portion thereof.

Fig. 5

Fig. 4

I claim:

The ornamental design of a portfolio, substantially as shown.
